United States Patent

Des. 237,762
Patented Nov. 25, 1975

237,762

ARROW STAND

R. Lynn Hendry, 840 Grelle, Lewiston, Idaho 83501

Filed Apr. 18, 1974, Ser. No. 461,989

Term of patent 14 years

Int. Cl. D6—99

U.S. Cl. D6—20

FIG. 1 is a perspective view of an arrow stand showing my design;

FIG. 2 is a side elevation view;

FIG. 3 is a top view;

FIG. 4 is a bottom view; and

FIG. 5 is a sectional view taken along line 5—5 in FIG. 2.

I claim:

The ornamental design for an arrow stand, as shown.
